RECORD-CARD CONTROLLED PRINTING MECHANISM

Alfred Augustus Dark, Letchworth, England, assignor to International Business Machines Corporation, New York, N. Y., a corporation of New York

Application June 7, 1938, Serial No. 212,248
In Great Britain June 16, 1937

13 Claims. (Cl. 197—20)

This invention relates to record-card controlled printing mechanism. Perforated record cards are divided into columns each usually containing twelve hole positions so that twelve characters can be represented in a column each by a single hole in a different position. The lower ten positions in the column are usually allocated to the digits 0 to 9, while the two upper positions are used for recording 10 and 11 when recording pence. In order to record more characters, for example, the letters of the alphabet, combinations of holes are employed. Thus an additional twenty characters can be recorded by using a hole in one of the lower positions together with the hole in one or other of the upper two positions. By this code it is possible to record any one of thirty-two characters in a column. There are thirty-six characters in the digits 0 to 9 and the letters of the alphabet combined, and, in order that these may all be recorded in one column, it is the practice to use the holes that represent 0, 1, 6 and 8 also to represent the letters O, I, G and S. When printing under the control of a card punched in this code specially formed type is used to print the digits 1, 6 and 8, so that these characters will be read as the letters I, G and S when they form part of a word. This code involves using the two upper positions to represent two letters of the alphabet each by a single hole.

It will be appreciated that any one of twelve characters can be recorded in the column using a single hole only for each character, or any one of a greater number of characters can be recorded if combinations of holes are employed. It is frequently desirable, however, to record on a card any one of one group of characters in one column and any one of another group of characters in another column. Thus, a card may have words recorded on it in the code referred to above and may also have, in another part of the card, amounts in sterling recorded. In recording such amounts the two upper positions are employed to represent 10 and 11 by single holes in the columns in which the pence digits are recorded. Thus, these hole positions represent 10 and 11 in certain columns of the card and letters of the alphabet in other columns of the card. Another example of this is when the hole positions in a column are employed to record different kinds of transactions, such as credit or debit transactions, or different classes of goods, and in such cases it may be desirable to print special symbols under the control of the holes in these columns.

This use of a hole or group of holes to represent different characters does not lead to confusion when printing from the card by means of printing mechanism of the kind comprising a plurality of type carriers each arranged to be con-

trolled by a different column of the card since each type carrier can be provided with type appropriate to the characters that will be represented in the column controlling it. Difficulty, however, arises when the card is used to control printing mechanism of the kind having only a single set of type which is employed to print the character represented in each column in turn, and it is the object of this invention to overcome this difficulty.

The present invention is, therefore, concerned with the record-card controlled printing mechanism of the kind comprising printing mechanism for printing a single character at a time, a hole-reading device arranged to read a single column on a card and to cause the printing mechanism to print the character represented by the hole or holes in the column read and card-feeding means for feeding the card step by step so that each column is read in turn. Such printing mechanism will be referred to hereinafter as printing mechanism of the type specified.

According to a feature of the present invention the printing mechanism is arranged to print any one of several characters in response to a particular hole or a particular hole configuration in a column and there is provided a selecting means which is operable in step with the movement of the card to render the printing mechanism operable to print one character while predetermined columns are being read and operable to print another character while other predetermined columns are being read.

It will be appreciated that the hole or hole combination in question will represent one character when it occurs in one column and another character when it occurs in the other column and the printing mechanism will print the proper character dependent upon the column in which the hole or hole combination occurs.

Preferably the printing mechanism is normally operative to print a predetermined one of the characters and the selecting means comprises a member which moves with the card and which is adjustable relatively to the card in the direction of its movement and means operated by the member when it reaches a predetermined position to adjust the printing mechanism to be operative to print the other character. The said means may be arranged to remain operative once it has been operated by the member so that the printing mechanism will print one character in response to the particular hole or hole combination if the latter occurs in one half of the card and the other character if the hole or hole combination occurs in the other half of the card.

According to another feature of the present invention the printing mechanism comprises a plurality of type levers each arranged to print a single character, and a plurality of electro-mag-

nets or solenoids each arranged to actuate a different type lever and having their energising circuits controlled by the card reading device, and the selecting means comprises an electro-magnetic relay arranged normally to interrupt the energising circuit of one of the said electro-magnets or solenoids and to make a connection in the energising circuit of another of the said electro-magnets but arranged when energised, to make connection in the circuit of the first electro-magnet and interrupt the circuit of the second electro-magnet, the card reading device being arranged to make a connection in both said circuits when it reads a particular hole or hole combination so that one or other of the circuits will be completed, dependent upon the condition of the relay.

According to a further feature of the invention, the printing mechanism is arranged to print on the card which is being read by the card-reading device so that the character recorded in each column by holes in that column is printed in that column.

Two machines in accordance with the present invention will now be described, by way of example only, with reference to the accompanying drawings, in which:

Figure 1 is a partial circuit diagram for the first machine.

Figure 2 is a partial circuit diagram for the second machine.

Figure 3 is a side elevation of a card-reading device in the second machine.

Figure 4 is a plan of the card-reading device.

Figures 5 and 6 show modifications that may be made to the circuits shown in Figures 1 and 2, and

Figure 7 is a vertical section through the first machine.

The first machine

The invention will first be described as applied to the typewriter punch shown in United States Patent No. 2,046,082, issued to A. W. Mills, which contains a full description of the machine. The present description will be confined to the modifications necessary to incorporate the present invention in the machine since these modifications do not involve any substantial alteration to the machine described in the above United States patent. Before describing the present improvements, a general explanation as to the operation of the machine will be given to aid in an understanding of the modifications made to it.

The machine comprises a type-writing and punching mechanism which is shown in Figure 7. As this mechanism is identical with that described in the Mills patent referred to above it need only be described briefly herein. The mechanism comprises a plurality of keys 230 each of which can be operated manually or by means of a related key-selecting solenoid KSS. When energized each solenoid KSS rocks a lever 503 to pull the related key 230 downwards by means of a link 505. Each key is returned by means of a spring 264 and rocks about a pivot 261. When a key is depressed its tail 271 moves away from a lug 272a on an operating hook 272 so that this hook can be rocked by means of a spring 273 clockwise about a pivot 258. The nose 272c of the hook is then moved into the path of a constantly rotating fluted actuator 74 which draws the hook 272 to the left. After the hook 272 has been moved

to a predetermined extent, the next flute on the actuator 74 engages a lug 272b on the hook and depresses the hood to disengage it from the actuator. Provision is made, as described in the Mills patent aforesaid, for preventing the hook re-engaging the actuator if the key is not promptly released.

Each hook 272 is pivoted at 258 on the end of a separate slide 257 and to a separate bell-crank lever 259. Thus, as the hook moves to the left it rocks the bell-crank lever 259 clockwise about its pivot 260 and also moves the slide 257 to the left. The bell-crank lever 259 rocks a lever 258 about a pivot 251 against the tension of the spring 253. The lever 258 has a pin 248 engaging in a slot in a type-lever 234 which is pivoted at 238. The type-lever is thus rocked to a position where a type 239 on it strikes a suitable inking ribbon against the top margin of a card which is supported in front of a platen roller 123. It will be appreciated that there is a separate type-lever for each key and each type-lever carries an appropriate character. In this manner printing is effected along the top edge of the card.

Each slide 257 is provided with one or two lugs 257c so that, when it is moved to the left, it rocks one or two balls 295. Each slide rocks a different ball or pair of balls. When rocked, each ball moves a slide 292, similar to the slide 257, to the left. This slide 292 is connected to a bell-crank lever 291 which is pivoted at 214. Thus, when each ball 295 rocks, it rocks a related one of the bell-crank levers 291. Each bell-crank lever 291 is connected by a link 290 to one arm 289 of a bell-crank lever which is pivoted at 287. The other arm 288 of each bell-crank lever is connected to a separate punch 280 so that the rocking of a bell-crank lever 291 will cause a related punch 280 to perforate the card.

In this manner the depression of a key 230 either manually or by means of the related key solenoid KSS causes a particular character to be printed at the top of a column on the card and also causes a hole or two holes, representing that character, to be punched in the same column.

The card on which printing and punching is to be effected is supported by guide rails 120 and 121 and is fed by means of two fingers 175 which engage the leading and trailing edges of the card. These fingers are carried by a frame or card carriage 174 which is slidably mounted on a rail 130. After each punching and printing operation the carriage 174 moves one step under control of escapement mechanism which is fully described in the Mills patent aforesaid. Thus, printing and punching of the card is effected column by column.

The machine is provided with a card-reading table 420 on which a perforated master card can be placed. This master card is fed in step with the blank card on which printing and punching is to be effected by means of two arms supported by the card carriage. One of these arms is shown at 460. The card is fed to bring each column in turn above a row of brushes MB and beneath a contact roller CR. The brushes MB correspond to the brushes B10 to B12 of the Mills patent aforesaid. Each column of the master card can thus be read by the brushes in turn and can control the solenoids KSS to print and punch on the blank card the information recorded by the holes of the master card.

When a hole in the master card comes beneath one of the brushes MB, that brush will engage the contact roller CR to complete a circuit extending from a wire W1 (Figure 1) through contacts R15—A, R30—B, BSC, R18—B, TSC, EC, PBC2, R14—B, and KIC, a common brush CBI, the contact roller CR, the brush MB which has found a hole and the connected relay coil of twelve relay coils R8 to R9, R11 and R12. If the circuit extends through one of the coils R8 to R9 inclusive, it will extend through relay coils R13 and R21 also. If the circuit passes through the relay coil R11 or the relay coil R12 it will include the relay coil R21 only.

Assume first that the column under the brushes MB contains a "9" hole only. The circuit just traced would then include the relay coils R9, R13 and R21. The coil R9 closes its contacts R9—A which are in parallel with the contacts KIC and CR to maintain itself and the coils R13 and R21 energised. The coil R9 also closes its contacts R9—B, R9—C, R9—D to complete a circuit extending from the wire W1 through the contacts R15—A, R30—B, BSC, R18—B, TSC, EC, PBC2, R14—B and R9—B, the key solenoid KSS related to the type-bar for printing 9, a wire W20, contacts R11—D and R12—D and a wire W2. The contacts R11—D and R12—D are closed since the related coils R11 and R12 are not energised. In this manner one key solenoid KSS is energised and causes its type-lever 234 to be actuated to print 9 at the top of the column of a blank card and also causes the selection of a punch for perforating a "9" hole in this column. No circuit can be completed through the contacts R9—C and R9—D to the key solenoids KSS for M and Y and the wires W21 and W22 because the wires W21 and W22 are disconnected from the wire W2 by the open contacts R11—C and R12—C of the relays R11 and R12.

Next assume that a particular column under the brushes MB contains both a "9" hole and an "11" hole. In these circumstances the relay coil R11 will be energised as well as the relay coil R9. The relay coil R13 will also be energised. The relay coil R11 will open its contacts R11—D to disconnect the line W20 from the line W2 and will close its contacts R11—C to connect the line W21 to the line W2. The closure of the contacts R9—B will not complete a circuit through the key solenoid KSS for 9 because the line W20 is not connected to the line W2. The closure of the contacts R9—C will, however, complete a circuit through the key solenoid for M, the line W21, the contacts R11—C and the contacts R12—D. The key solenoid for M will thus be energised and will cause its type-lever 234 to be actuated to print M and select the punches for punching a "9" and an "11" hole in the appropriate column of the blank card.

In a similar manner when a "9" and a "12" hole is present, the relay coil R12 will be energised and will open its contacts R12—D to prevent the key solenoids KSS for 9 and M being energised. The coil R12 will also close its contacts R12—C so that a circuit can be completed through the contacts R9—D, the key solenoid KSS for Y, the line W22 and the contacts R12—C.

As soon as the type-lever and the punches have operated to print and punch a column of the blank card, both the blank card and the master card escape one step under the control of escapement mechanism. During this escape-

ment movement the contacts EC are opened and de-energise the energised relay coil in the group R8 to R9, R11 and R12 and also the coil R13 and R21 and the energised key solenoid KSS. This restores the circuits to normal in readiness for reading the next column in the master card and for printing and punching in the next column of the blank card. It may be mentioned that the contacts R15—A, R18—B and R14—B are controlled by the relays R15, R18 and R14, described in the Mills patent. These relays are controlled by the circuits shown in this patent and these circuits have been omitted from the present patent. The contacts BSC, TSC, EC, PBC2 and KIC are arranged and operate in the same way as the correspondingly designated contacts in the prior patent. The contacts R30—B are closed in a manner which will be described later and form part of the present improvements.

The manner in which the machine operates when a hole is present in one of the hole positions "0" to "9" alone or in combination with an "11" hole or a "12" hole is similar to that described above and need not be further described herein. It may be mentioned that all the key solenoids are not shown in Figure 1 but the arrangement of the circuits for the remaining key solenoids is analogous to those shown. The manner in which the machine operates when an "11" hole or a "12" hole is present alone will be described later.

The machine is provided with tabulating mechanism which is fully described in the Mills patent referred to above. This mechanism comprises a stop-bar 300 (Figure 7) which moves with the cards and which is provided with slots. Stops 302 may be mounted on this bar in various positions and move with the bar which travels underneath a group of levers 381. Each stop 302 is provided with a projection 302b which is adapted to engage and rock one of the levers 381 when a particular column of the master card is under the brushes and the corresponding column on the blank card is in position for printing. The particular column depends on the position of the stop on the stop-bar. Each lever closes and/or opens contacts which control various operations of the machine, such as commencement of duplication from a master card, the termination of duplication from a master card and the ejection of a blank card. There are five such stops which are referred to in the Mills patent as stop No. 1 to stop No. 5. The stops differ from one another in respect to the position of their projections 302b. Owing to this difference each stop will operate a different lever 381 and is appropriate to a different operation.

When a master card is on the card-reading table it closes card-lever contacts CLC. The master card is held in position on the table by a door which must be closed and, when closed, closes contacts DC. When both these pairs of contacts are closed a circuit is completed to energise a magnet BM. This circuit extends from the wire W1 to the contacts R15—A, R30—B, BSC and R18—B, the magnet BM and the contacts DC and CLC. The magnet BM, when thus energised, serves to move the brushes MB into contact with the card. When the magnet BM is de-energised the brushes MB are moved by spring means away from the card so as not to interfere with a movement of the master card backwards. The magnet BM is de-energised when the cards are back-spaced, the contacts BSC being opened during back-spacing operations for this purpose. It is also de-energised

during the so-called "ejecting operation". An ejecting operation is performed automatically, as described in full detail in the Mills patent referred to above after the blank card has been fed fully past the printing and punching position and during this operation the blank card, on which printing and punching has now been effected, is ejected, the master card is returned to its initial position in readiness for the printing and punching operations on the next card and a new blank card is fed from a magazine to the card carriage which serves to move the card step by step through the printing position. The card-ejecting mechanism is identical with that described in the Mills patent aforesaid and need not be described herein.

If a column on the card is blank, both cards will automatically escape a column in the following manner. It has been mentioned that the contacts EC open when the card escapes. When they reclose a circuit is completed through the contacts R15—A, R30—B, BSC, R18—B, TSC, EC, PBC2, R14—B and KIC, contacts CS2, a relay coil R20 and a wire W14. The relay R20 closes its contacts R20—A to complete a parallel circuit extending from the contacts R14—B through a switch SS, relay contacts R21—A, the contacts R20—A and escapement magnet EM and contacts LCC2. The escapement magnet EM operates the escapement mechanism so that both cards will escape one column. The escapement magnet EM operates in the same way as the magnet EM shown in the Mills patent aforesaid. The circuit to the relay coil R20 is completed whether or not there is a hole in a column. If, however, there is a hole in a column the relay coil R21 will be energised as described previously. The relay coil R21 will open its contacts R21—A in the circuit through the escapement magnet EM. The relay coil R20 is arranged to be substantially slower in operation than the relay coil R21 so that, if both these coils are energised at the same time, the contacts R21—A will be opened before the contacts R20—A close. Thus, the circuit through the magnet EM will not be completed if there is a hole in the card and the relay coil R21 is energised and opens its contacts R21—A. This circuit will, however, be completed if there is no hole in the card.

The above briefly describes the operation of the prior machine and reference should be made to the Mills patent aforesaid for a more detailed description of the machine.

It should be mentioned that the present machine is arranged to record the digits and the letters of the alphabet by a different hole code to that described in the prior Mills patent. This code is shown in the following table.

	12	11	10	12
12	Z,11	—	—	—
11	A,10	—	—	—
0	0,O	B	N	—
1	1,I	C	P	—
2	2	D	Q	—
3	3	E	R	—
4	4	F	T	—
5	5	H	U	—
6	6,G	J	V	—
7	7	K	W	—
8	8,S	L	X	—
9	9	M	Y	—

In the above table the first column shows the hole positions, the second column shows the characters represented by single holes, the third col-

umn shows the characters represented by a hole in one of the "0" to "9" positions in combination with a hole in the "11" position and the fourth column shows the characters represented by a hole in one of the 0 to 9 positions in combination with a hole in the "12" position. It should be mentioned that "1" and "I" are printed by the same type lever which has a type for printing a character that can be read either as "1" or "I". The same applies to "6" and "G" and to "8" and "S". The hole in the "11" position, when it occurs, alone, represents either "A" or 10, while a single hole in the "12" position represents either "Z" or 11. These four characters are printed by four separate type-levers and "A" or "Z" will be printed if an "11" or "12" hole occurs in certain columns, while 10 or 11 will be printed if the "11" or "12" hole occurs in other columns.

It may be mentioned that the circuits through the key solenoids KSS are shown in Figure 1 arranged in accordance with the above code and are not therefore exactly the same as those described in the Mills patent aforesaid.

It is the practice to record all the information involving the use of letters on the left-hand part of the card, for example in the first twenty-two columns, while information involving numerals only is recorded in the remaining columns on the right. Thus, 10 or 11 will only be recorded in one of the columns to the right of column 22 and will not be recorded in columns 1 to 22 inclusive. The proper recording of A, Z, 10 and 11 is effected by the following selecting means.

The machine is provided with a card lever (not shown) which is engaged by each card fed from the magazine and rocked to close contacts CLC2 as the blank card passes from the magazine to the card-carriage by which it is moved step by step through the printing position. As soon as the card has been received by the carriage, it releases the card lever and the contacts CLC2 re-open. This card lever is mounted adjacent the feed roller 143 shown in Figure 6 of the Mills patent aforesaid with its end that is engaged by the card located to the right, as seen in that figure, of the shaft on which that feed roller is mounted and just above the feed roller.

The closure of the contacts CLC2 completes a circuit through a relay coil R30 which closes its contacts R30—A to provide a holding circuit for itself through cam contacts CS5. These contacts are operated by a cam which rotates with the cams for operating the contacts CS1 to CS4 shown in the Mills patent aforesaid. These cams rotate during the ejecting operation only. The contacts CS5 are normally closed and are timed to open at 70° and close at 225° in the movement of the cam. The card lever contacts CLC2 are timed to close when these cams have turned through 120° and to re-open when the cams have turned through 255°. Thus, the contacts CS5 will have re-closed while the contacts CLC2 are closed to maintain the relay coil R30 energised. When the card which caused the contacts CLC2 to close is ejected in the next ejecting operation, the contacts CS5 open to de-energise the coil R30. They then re-close so that the holding circuit for the coil R30 may be re-established if another blank card has been fed and has closed the contacts CLC2.

The coil R30 will thus be energised each time a card is fed from the magazine to the card-carriage and will remain energised until that card is ejected from the card-carriage. It will then be de-energised and shortly afterwards will

be re-energized if another blank card is fed from the magazine. The coil R30 closes the contacts R30-B previously referred to.

A special stop 302 (Figure 7) is mounted on the stop-bar 300 in the column 23 position so that, when column 23 of the master card is under the brushes MB, this stop will engage and rock a special lever 387 to close print-selecting contacts PSC1 (Figure 1). The special lever is similar to the levers 387 shown in the Mills patent aforesaid and is mounted beside those levers. The special stop which will be referred to as the No. 7 stop is similar to the stops 302 shown in the Mills patent aforesaid except that its lug is placed to engage the special lever 387 in the same fashion as described in the Mills patent aforesaid with reference to the lugs 302b shown therein.

Thus, when the column 23 arrives under the brushes MB, the No. 7 stop will close the contacts PSC1 to complete a circuit through them, a relay coil R31 and the contacts R30-B and R15-A. The coil R31 will close its contacts R31-A to complete a holding circuit through contacts PSC2 and a switch APS. The coil R31 will thus remain energised until the coil R30 is de-energised in the next ejecting operation and opens its contacts R30-B.

The coil R31 has a pair of normally closed contacts R31-B in circuit with the key solenoid KSS for A and a pair of normally closed contacts R31-D in circuit with the key solenoid for Z. While the first twenty-two columns on the card are being read, the relay coil R31 will be de-energised and its contacts R31-B and R31-D will be closed. If an "11" hole occurs alone in one of these twenty-two columns, the coil R11 will be energised and the contacts R11-B will be closed. The circuit can then be completed through the contacts R15-A, R30-B, BSC, R18-B, TSC, EC, PBC2 and R14-B, contacts R13-A, the contacts R11-B, the contacts R31-B, the key solenoid KSS for A and the contacts R11-C and R12-D. This solenoid will actuate its type-lever to print A and will also cause the selection of a punch to punch an "11" hole. If a single hole occurs in the "12" position of one of the first twenty-two columns, the relay coil R12 is energised and then closes its contacts R12-B. A similar circuit is then completed which includes contacts R13-A, R12-B and R31-D, the key solenoid KSS for Z and the contacts R12-C. The solenoid actuates its type lever to print Z and causes the punching of a hole in the "12" position.

It should be pointed out that the above two circuits through the key solenoids for A and Z cannot be completed if the "11" or "12" holes are accompanied by a second hole in one of the positions "0" to "9." This is because the presence of a hole in the positions "0" to "9" completes a circuit through the related coils R6 to R9 and the relay coil R13. This coil opens its contacts R13-A to interrupt the previously traced circuits to the solenoids for A and Z.

When the 23rd column is under the brushes MB, the relay R31 is energised as explained above and opens its contacts R31-B and R31-D, closing its contacts R31-C and R31-E. The presence of an "11" hole alone will, as before, result in the contacts R11-B closing and the contacts R13-A remaining closed but the circuit will now extend through the contacts R13-A, R11-B and R31-C, the key solenoid KSS for 10 and 75

the contacts R11-C and R12-D. The key solenoid for 10 will actuate its type-lever to print 10 and select a punch to perforate the "11" position on the blank card. In the same way, the presence of a "12" hole alone in a column will result in the contacts R12-B closing and a circuit being completed through the contacts R13-A, R12-B and R31-E, the key solenoid KSS for 11 and the contacts R12-C. This key solenoid will actuate its type-lever to print 11 and will select a punch to perforate the "11" position in the column of the blank card.

It will be noticed that the "11" or "12" hole appearing on the master card will be duplicated on the blank card but that A or Z will be printed when the relay R31 is de-energized and 10 or 11 will be printed when that relay is energized. Thus A and 10 are alternative characters and Z or 11 are alternative characters. This is merely a matter of placing the appropriate type on the appropriate type-lever so that any pairs of alternative characters can be printed. Any number of alternative characters can be provided for, it being only necessary to provide the selecting relay with the proper number of closed and open contacts connected to the proper solenoids. For example, the contacts R8-D could be disconnected from the key solenoid KSS for N and connected to the centre plate of a set of triple contacts similar to the contacts R31-C and R31-E. The normally closed contact of this set could be connected to the key solenoid for N while the normally open contact of this set could be connected to a solenoid which causes the printing of a special symbol such as the symbol "Cr" which indicates that the amount is a credit amount. With this arrangement the occurrence of a "0" and "12" hole in the first twenty-two columns of the card would result in the key solenoid for N being energised while the occurrence of the same pair of holes in the remainder of the card would result in the key solenoid for the special symbol being energised and that symbol printed. In each case "0" and "12" holes would be punched in the appropriate column of the blank card.

In certain cases the alphabet and numerical information cannot be divided in the simple manner suggested above. Thus, it may be desirable to include, in cards relating to goods, the price of the goods in the part of the card containing alphabet information. In such cases the machine should only print 10 and 11 in the columns which are allocated to receive pence amounts. To provide for this a No. 7 stop may be placed on the stop-bar in the positions corresponding to such columns and the switch APS may be opened. The effect of this is that the relay R31 cannot establish a holding circuit for itself through the contacts R31-A so that it will only be energised when the contacts PSC1 are closed. These contacts will be closed by the No. 7 stop while the columns in which pence are recorded are under the brushes MB. Thus, 10 and 11 will only be recorded in the corresponding columns of the blank cards and A and Z will be printed where an "11" or "12" hole occurs in any other column of the master card.

If it is desired to record numerical information, in, say, columns 20 to 30 and alphabetical information to the left and right of columns 20 and 30, a No. 7 stop may be placed in the column 20 position and a No. 8 stop in the column 31 position. A No. 8 stop will be similar to the other stops 302 except that its projection 302b

is so disposed that it will rock a second special lever to open contacts PSC2. These contacts are included in the holding circuit for the relay R31 so that the relay R31 will be de-energised when they open. Thus, the relay R31 will only be energised while columns 20 to 30 on the master card are being read and 10 and 11 can only be printed under the control of those columns.

The second machine

The manner in which the invention can be applied to a card interpreter will now be described. A card interpreter is a machine for printing on a card the information recorded by the holes in the card. The present machine is structurally the same as the machine described in United States Patent No. 2,046,082, issued to A. W. Mills, aforesaid except that the punching mechanism is removed and is replaced by a lower card-reading device. This device is shown in Figures 3 and 4. Printing is effected on the platen roller 129. The card-reading device comprises twelve brushes LB which are held each by means of a separate stud 1000 on a bar 1001 of insulating material. This bar is pivoted in ears 1002 on a fixed bracket 1003 and extends vertically behind the card on which printing is to be effected. Each stud is engaged by a separate spring blade 1004 which serves electrically to connect the brush to a terminal 1005. The terminals and the blades are carried by a fixed bar 1006 of insulating material. The blades also serve to rock the insulating bar 1001 in its bearings about a vertical axis so that the brushes will bear against the back surface of the card. The brushes will engage the column of the card which is at the printing position and, if a hole is present in this column, the corresponding brush will extend through the hole and make contact with a vertical conducting strip 1007 mounted in front of the card in a fixed insulating support 1008.

The bar 1001 is provided with a lug 1009 which engages a notch 1010 in a slide 1011. This slide is supported by pin-and-slot connections 1012 on the bracket 1003 so that it can move vertically. The slide 1011 serves to limit the movement of the bar 1001 so that the pressure of the brushes on the card will not become excessive. The slide 1011 is connected at 1013 to a link 1014 which is pivoted on a bail 179. This bail is pivoted at 181 and is connected to a link 183, the lower end of which co-operates with a cam 184 on a shaft 100. The parts 179, 181, 183 and 184 and 100 are the same as the corresponding parts shown in the Mills patent previously referred to. As explained in that patent, the shaft 100 turns through a revolution during each ejecting operation and the cam 184 depresses the link 183 so as to raise the bail 179 and rock the card-feeding fingers 175 about a pivot 177. These fingers are rocked during the ejecting operation so as to move them behind the plane of the card in order that the card on which printing has just been effected may be fed into the card receiving hopper and a new card fed into position between the fingers.

When the bail 179 is thus raised it raises the link 1014 and the slide 1011. This moves the notch 1010 above the lug 1009 and cams this lug forwardly so that the bar 1001 is rocked and the brushes LB are moved clear of the card. It will thus be seen that the brushes are moved clear of the card while the card is being ejected and a new card is being fed in.

Except as just explained, the present machine will be structurally identical with that described in the Mills patent referred to above.

The circuits of the second machine are shown in Figure 2 in so far as they differ from the circuits shown in the Mills patent referred to above. The circuits shown in Figure 2 are the same as those shown in Figure 1 except for the inclusion of the brushes LB and a master card multi-relay. The coil MCR of this relay is connected in series with the brush magnet BM. The relay has normally open contacts MCR-B which are connected one between each brush MB and the related coil R8 to R9, R11 and R12. The relay has also normally closed contacts MCR-A which are connected one between each lower brush LB and the related coil R8 to R9, R11 and R12.

If the coil MCR is de-energised, the brushes MB will be disconnected and the brushes LB will be connected in circuit each with the related coil R8 to R9, R11 and R12. Thus, these relay coils will be energised in accordance with the holes provided in the cards on which printing is to be effected. These cards are pre-punched and are placed in the magazine from which they are fed one by one. The machine operates to read each column on these cards and print at the head of that column the character recorded by the holes in it. The manner in which the relays R8 to R9, R11 and R12 control the key-selecting solenoids KSS is exactly the same as described with reference to Figure 1 so that it need not be repeated. If it is desired to interpret the information on a card, no master card is placed upon the reading table so the contacts CLC will be open and the magnet BM and the relay coil MCR will not be energised. The relay coils R8 to R9, R11 and R12 will then be controlled by the brushes LB as just explained.

It may, however, be desired to print on all of the cards certain information which is common to all of them but which is not represented by holes on the cards. In such a case, this information will be recorded by holes in the master card which will be placed in the card-reading table. When this master card is inserted, the contacts DC and CLC are closed so that the magnet BM and the relay MCR are both energised. The relay coil MCR then opens its contacts MCR-A and closes its contacts MCR-B connecting the brushes MB to the coils R8 to R9, R11 and R12 and disconnecting the brush LB from those coils. The operation of the mechanism will then be exactly as described with reference to Figure 1 except that the information on the master card is printed but is not punched on the other card.

Modified circuits

It will be appreciated that the machine may be modified to deal with cases in which a single hole or pair of holes may represent more than two characters. Thus, it is the practice to use the "11" and "12" holes to indicate whether an amount recorded on the card is a credit or a debit. These holes are also used to record the eleventh and twelfth months of the year, the tenth month being recorded by a "0" hole. An "11" hole may thus represent either A, 10, 11 or credit, a "12" hole Z, 11, 12 or debit, while a "0" hole may represent 0 or 10. It will be assumed that the alphabetical matter, including a date, will appear in the first twenty-two columns of the card and numerical matter will appear in the remaining columns of the card. It will

further be assumed that the month in the date will be recorded in column 15 and that an "11" hole in column 30 will indicate a credit, and a "12" hole in column 30 will indicate a debit. The No. 7 stop will be placed in the column 23 position and No. 9 stops will be placed in the column 15 and the column 30 positions. The No. 9 stops are similar to the other stops except that they close contacts PSC3 (Figure 5).

When the 23rd column of the master card is 10 under the brushes MB, the No. 7 stop will close the contacts PSC1 (Figure 5) to energise the relay coil R31. This coil closes its contacts R31—A 15 to maintain itself energised, as before, until the next eject operation. As before, the presence of an "11" or "12" hole in the columns 1 to 14 and 16 to 22 will cause the completion of a circuit to energise the solenoids KSS for A or Z respectively. The presence of an "11" or "12" hole in one of the columns 23 to 29 and 31 onwards will cause 20 the completion of a circuit to energise the solenoids KSS for 10 or 11 respectively. The circuits will be as previously described except that they will include normally closed relay contacts R32—A (Figure 6). The circuit establish when a "0" 25 hole occurs in one of the above columns will include the contacts R0—B, contacts R32—C, the solenoids KSS for 0 and the contacts R11—D and R12—D.

When the 15th column of the master card is 30 under the brushes MB, the No. 9 stop will close contacts PSC3 (Figure 5) to energise a relay coil R32. This coil has no holding circuit so that it will be de-energised as soon as the No. 9 stop moves to the 16th column position. The coil 35 R32 opens the contacts R32—A and R32—C (Figure 6) and closes contacts R32—B and R32—D. Thus, if there is a "0" hole present in column 30 the contacts R0—B will close, as explained before, to complete a circuit through the contacts R32—D and a key solenoid KSS which controls the printing of "10". In the same way the presence of an "11" hole in column 15 will result in 40 a circuit being completed through the contacts R11—B, R31—B and R32—D to energise a key solenoid which controls the printing of "11". A "12" hole in column 15 results in the solenoid KSS for 12 being energised through the contacts R12—B, R31—D and R32—B.

The relay R32 is again energised for the column 30 position owing to the No. 9 stop closing the contacts PSC3. At this time the relay R31 is energised so that an "11" hole causes a circuit to be completed through the contacts R11—B, R31—C and R32—B to energise a solenoid KSS which controls the printing of a symbol "Cr". A "12" hole in column 30 will result in a circuit through the relay contacts R12—B, R31—E and R32—B and a key solenoid KSS for the symbol "Dr". The circuits shown are designed for cases when the only holes that will be punched in column 30 will be in the "11" or "12" positions and a "0" hole in this column would result in "10" being printed. It may be desirable that the other hole-positions in this column 30 should have special significance and control the printing of special characters and it is merely necessary to provide the relays R31 and R32 with extra contacts controlling the appropriate solenoids KSS in the manner just described.

It will be noticed that the solenoids for 10 and 11 are duplicated. This is purely for convenience in connecting them in circuit and the duplicated solenoids may have a common core and operate the same type-lever.

It will be appreciated that the invention is not restricted to machines controlled by cards in which letters of the alphabet are recorded by pairs of holes but can be applied also to machines controlled by cards in which only the digits are recorded by single holes.

I claim:

1. A record card controlled printing mechanism comprising a hole-reading device arranged to read a single column on a card containing any of a plurality of hole configurations at least one of which configurations represents either of two alternative characters, printing mechanism arranged to print any of the characters represented by the possible hole configurations in a column of the card, one character at a time, which printing mechanism is arranged normally to print a predetermined one of said alternative characters, card-feeding mechanism for feeding the card step by step so that each column is read in turn, a member which moves with the card and which is adjustable relatively to the card in the direction of its movement and means operated by the member when it reaches a predetermined position to adjust the printing mechanism to print the other character.

2. A record card controlled printing mechanism comprising a hole-reading device arranged to read a single column on a card containing any of a plurality of hole configurations at least one of which configurations represents either of two alternative characters, printing mechanism arranged to print any of the characters represented by the possible hole configurations in a column on the card, one character at a time, which printing mechanism is arranged normally to print a predetermined one of said alternative characters, card-feeding mechanism for feeding the card step by step so that each column is read in turn, a member which moves with the card and which is adjustable relatively to the card in the direction of its movement, means rendered operative by said member when the latter reaches a predetermined position to cause the printing mechanism to print the other character, holding means arranged to maintain the last named means in operative condition once it has been rendered operative by the member, and restoring means for rendering said holding means inoperative.

3. A record card controlled printing mechanism comprising a hole-reading device arranged to read a single column on a card containing any of a plurality of hole configurations at least one of which configurations represents either of two alternative characters, printing mechanism arranged to print any of the characters represented by the possible hole configurations in a column on the card, one character at a time, which printing mechanism is arranged normally to print a predetermined one of said alternative characters, card-feeding mechanism for feeding the card step by step so that each column is read in turn, a member which moves with the card and which is adjustable relatively to the card in the direction of its movement, means operated by the member when it reaches a predetermined position to adjust the printing mechanism to print the other character, which means is arranged to 60 remain operative once it has been operated by the member, restoring means operative to render said means inoperative and a second member which moves with the card, which is adjustable relatively to the card in the direction of its movement and which is arranged to operate the

restoring means when it reaches a predetermined position.

4. A record card controlled printing mechanism comprising a hole-reading device arranged to read the hole configuration in a single column on the card at a time, which configuration represents any of a plurality of characters arranged in two groups, printing mechanism for printing any of said characters when said hole configuration is read, a first selecting means which is operative to cause the printing mechanism to print a character from one group of the characters or from the other group of characters alternatively and a second selecting means which is operative to cause the printing mechanism to print one or another character within a selected group of characters, means for feeding the card column by column so that each column is read in turn and means including a member movable in step with the card to render either or both selecting means operative when a predetermined column of the card is in register with the hole-reading device.

5. A record card controlled printing mechanism comprising a plurality of type-levers each arranged to print a single character, a plurality of electromagnets each arranged to control the operation of a different type-lever, a card-reading device, an energizing circuit for each electromagnet which circuits are controlled by the card-reading device and completed selectively in accordance with the hole configuration in a column read by that device, card-feeding means for feeding the card column by column so that each column is read in turn, an electromagnetic selecting relay arranged normally to hold open the energizing circuit of one of said electromagnets and to maintain a connection in the energizing circuit of another of said electromagnets but arranged, when energized, to close the circuit of the first electromagnet and to open the circuit of the second electromagnet, the card-reading device being arranged to make a connection to both said circuits when it reads a particular hole configuration; and means for energizing said relay when a predetermined column of the card is in register with the card-reading device, said means including a switching device for controlling said relay and a member movable in step with the reading of the card by the card-reading device for actuating said switching device.

6. A record card controlled printing mechanism comprising a card-reading device for reading any of a plurality of hole configurations in a card, each of which configurations corresponds to a different character and at least one of which configurations corresponds to at least two alternative characters, means for feeding the card so that each column is read in turn, printing mechanism arranged to print any of the characters represented by said hole configurations one at a time at the top of the column on the card in which the related hole configuration appears and selecting means which is operative in step with the movement of the card to render the printing mechanism operative to print one of said alternative characters while one predetermined column is being read and to print the other of said alternative characters while another predetermined column is being read.

7. A record controlled machine comprising a record sensing device for sensing data designations disposed in the columns of a record field, said sensing device being arranged to sense a single column at a time, said columns containing

designations representing characters to be printed, certain designations representing a plurality of characters, other designations representing single characters whereby predetermined 5 designations have a plurality of meanings and the remaining designations only one meaning for each; printing mechanism comprising a plurality of type elements, each type element representing a single character and operable independently of the others to print a single character upon a record medium; means to effect a relative movement between the sensing device and a record containing said designations whereby to sense the columns one at a time; selecting 10 means for controlling the operation of the printing mechanism to select the character to be printed; selection control means for coupling the selecting means to the sensing device, said selection control means coupling the selecting means for those type elements which correspond to designations having a plurality of meanings to the part of the record sensing device which 15 senses the corresponding designations, said selection control means normally causing the selecting means to operate in accordance with only one of the meanings of the predetermined designations and being operable to cause the selecting means to operate in accordance with other meanings of said predetermined designations; 20 and means, including a member movable in step with the sensing of the columns of the record by the sensing device and a device relative to which said member moves, for operating the selection control means only when predetermined columns 25 are sensed as determined by the position of said member.

8. In a machine of the class described, a series 30 of sensing elements each for sensing an index point position of a record column in which one or more designations may occur representing characters, certain of the characters being represented by combinations of designations and others of the characters being represented by a single designation, certain of said designations or combinations of designations each representing a plurality of different characters; means to cause a relative feeding movement between the sensing elements and the record to cause the columns of said record to be successively sensed, 35 printing mechanism for printing one character at a time and adapted to print any of the characters represented by said designations, a series of control elements each corresponding to a character and when operated controlling the printing mechanism to cause the corresponding character to be printed, selective control means controlled by the sensing elements for selectively controlling the operation of the control elements, means to connect the selective control means to certain of the control elements, said connecting means being selectively operable to couple different control elements to the selective control means, and means, including a member traveling in synchronism with the sensing of the record columns and a relatively fixed element engaged by said member, for operating the connecting means to change the effect of the designations in certain columns on the control elements.

9. In a machine of the class described, a record sensing device arranged to sense a single column at a time of a record field containing designations representing characters, certain of said designations representing a single character while others of said designations each represent a plurality of characters; means to cause a

relative movement between the sensing device and the record to sense said columns successively; recording mechanism including a series of control circuits, each circuit being associated with a particular character; means controlled by the sensing device for closing said circuits selectively according to the positions of designations in the record columns, a switching device for placing those of said circuits corresponding to a plurality of characters all of which are represented by the same designation under control of the circuit closing means controlled by the part of the sensing device which senses the common designation, and means including a member movable in step with the sensing of the record columns and an element engaged by said member, for controlling the switching device whereby different characters are caused to be printed on the occurrence of the same designation in different columns.

10. A record controlled machine comprising printing mechanism, a record sensing device arranged to read a relatively small area such as a column of a record which area may contain designations representing characters to be printed by the printing mechanism, at least one of which designations represents either of two alternative characters, said printing mechanism being arranged to print the characters designated in the record areas one at a time and to normally print the first of the alternative characters corresponding to designations which represent alternative characters; means to effect a relative movement between the sensing device and the record to cause the areas containing the designations to be sensed one area at a time; a member which is moved synchronously with the sensing of the record areas by the sensing device; and means, including a relatively fixed member cooperating with the first named member, to adjust the printing mechanism to print the second of the alternative characters when the record sensing device cooperates with predetermined areas on the record.

11. A record controlled machine comprising printing mechanism, a record sensing device arranged to read a relatively small area, such as a column, on a record which area contains data designations representing characters to be printed by the printing mechanism, at least one of which designations represents either of two alternative characters; said printing mechanism being arranged to print the characters designated in the record areas one at a time and to normally print the first of the alternative characters corresponding to designations which represent alternative characters; means to effect a relative movement between the sensing device and the record to cause the areas containing the designations to be sensed one area at a time; a member which is moved synchronously

with the sensing of the record areas by the sensing device; and means, including a relatively fixed member cooperating with the first named member, to adjust the printing mechanism to print the second alternative character when the record sensing device cooperates with predetermined areas on the record, one of said members being adjustable to predetermine the areas with respect to which the second alternative character is to be printed.

12. A record controlled printing machine comprising a record sensing device arranged to read a predetermined portion such as a single column of a record, each portion containing any of a plurality of designations, at least one of which designations represents either of two alternative characters; printing mechanism arranged to print any of the characters represented by the possible designations in a portion of the record one character at a time, said printing mechanism being normally arranged to print a predetermined one of the alternative characters; record feeding mechanism for feeding the record past the sensing device to cause the record portions to be sensed one portion at a time; a member movable in synchronism with the feeding of the record; and means, including a member which is relatively fixed and cooperating with the first named member, when it reaches a predetermined position, to adjust the printing mechanism to print the other of the alternative characters, one of said members being adjustable to predetermine the points in the feeding of the record at which the other alternative character is printed.

13. A record controlled printing machine comprising a device for sensing any of a plurality of character representations on a record, said character representations being disposed in predetermined areas arranged in a row on the record, certain of which areas may contain representations of at least two alternative characters; means for feeding the record past the record sensing device to sense the areas one at a time; printing mechanism arranged to print any of the characters corresponding to the character representations, said printing mechanism printing the characters one at a time as the character representations are sensed by the sensing device; and selecting means which is operable in step with the feeding of the record to render the printing mechanism operable to print one of the alternative characters while predetermined areas containing representations of alternative characters are being sensed and to print the other of the alternative characters while any other areas containing said representations are being sensed.
